ATTACHMENT PLUG

Edmund J. Te Pas, Rocky River, Ohio, assignor to
Walter A. Frantz, Cleveland Heights, Ohio

Application August 8, 1933, Serial No. 684,192

6 Claims. (Cl. 173—322)

This invention relates to electrical connectors as for example the terminal plug caps of attachment plugs for electrical cords and it has for its objects the provision of a device of this character which is not liable to breakage, which is not liable to electrical short circuiting, and which is not apt to become detached from the cord or to have the electrical connection broken between the plug contacts and the conductor strands of the cord, the aforesaid objects being accomplished through the use of a simple and inexpensive form of plug cap construction which can be readily attached to an electric cord by persons unskilled and inexperienced in the construction of electrical devices and appliances.

With these and other objects in view, the invention consists in the novel construction, arrangement and combination of parts, hereinafter illustrated and described in some of its embodiments in the accompanying drawing, and particularly pointed out in the appended claims.

In the drawing, Figure 1 is a side elevational view of a plug cap illustrative of one mode of practicing this invention; Figure 2 is a sectional view taken on line 2—2, Figure 1; Figure 3 is a plan view partly in section taken on line 3—3, Figure 2; Figure 4 is a side elevational view of another form of plug cap illustrative of the invention; Figure 5 is a sectional view taken on line 5—5, Figure 6; Figure 6 is a plan view partly in section taken on line 6—6, Figure 5; Figure 7 is a sectional view taken on line 7—7, Figure 8, of yet another form of plug cap illustrative of the invention; and Figure 8 is a sectional view of the plug cap taken on line 8—8 of Figure 7.

Three forms of plug caps are shown in the drawing for the purpose of illustrating some of the different ways of carrying out this invention. The body of the plug cap shown in Figures 1 to 3 comprises a cap 1 and an end part 2, the cap and end part being removably associated with each other and secured together in their assembled relation by means of two screws 3—3 which also serve to maintain electrical contact between the plug contact terminal blades or prongs 4 and the ends of the conductor strands 5 of an electrical cord 6.

The body parts 1 and 2 of the plug cap are arranged interiorly for receiving the cord 6 and also for receiving a body of soft rubber-like material 7 which normally loosely surrounds the end of the cord and which is tightly wedged in gripping relation about the cord when the body parts 1 and 2 of the plug cap are drawn together in their assembled relation by means of the

screws 3. The body parts 1 and 2 may be conveniently formed from an electrically non-conducting rigid material as for example vulcanite or one of the many other materials which are available and commonly used for this purpose. 5

Threaded bushings 8 are embedded in the cap 1 for receiving the threaded ends of the screws 3 by means of which the conductor strands 5 are connected to the contact prongs 4. A washer 9 which may be constructed of fiber or other electrically non-conducting materials is provided to cover the screws 3 and to complete the assembly of the plug.

The plug cap just described constitutes a simple and relatively inexpensive plug cap which 15 may be readily attached or detached with respect to an electric cord. The connecting of the plug cap terminals to the conductor strands of the cord serves automatically to anchor the plug cap to the cord whereby twisting of the cord with respect to the plug is prevented and to hold the parts of the plug cap in assembled relation. This result is achieved upon the tightening of the screws which are used to effect the electrical connection between the conductor strands of the 25 cord and the contact prongs of the plug, these screws also serving to secure the contact prongs in proper position. The aforesaid plug parts are of simple construction and the completed plug cap forms a highly useful device for the purpose 30 intended.

The modified form of plug cap shown in Figures 4, 5, and 6 comprises an outer sheath or shell 10 which is formed from a soft rubber-like electrically non-conducting material beyond one 35 end of which a pair of contact prongs 11 extend. The contact prongs are secured to a rigid part 12 of the plug by means of suitable rivets 13. A cooperating plug part 14 having threaded sleeves 15 cooperates with the part 12 to cause a soft 40 rubber-like body 16 to frictionally grip an electrical cord 17.

A pair of screws 18 are provided to connect the conductor strands 19 of the cord to the contact prongs 11, such screws serving at the same 45 time to draw the cooperating plug parts 12 and 14 towards each other whereby the member 16 is wedged in gripping relation with respect to the end of the cord 17. A suitable washer 20 is provided to cover the screws 18 and to complete the 50 assembly of the plug.

The plug parts 11, 12, 14 and 16 are constructed as separate elements of the plug which upon the completion of their manufacture may be readily assembled together whereupon the sheath 55

10 is fitted over such parts. The part 14 has a flange 14^a which fits in a suitable groove formed in the sheath and in this manner the sheath is retained in proper position on the plug cap. In 5 this form of the invention also the screws used to secure the conductor strands to the plug have the added function of locking the plug cap to the electrical cord.

The modified form of plug cap shown in Figures 10 7 and 8 comprises a soft rubber-like body 21 in which is embedded a rigid circular plate 22 having threaded sleeves 23 for receiving a pair of screws 24 by means of which the conductor strands 25 of an electrical cord 26 are secured 15 to a pair of suitable contact prongs 27 carried by a rigid plate 28. A suitable washer 29 is provided for covering the screws 24 and for completing the assembly of the plug. The disk 22 is provided with holes 30 to better insure its anchorage 20 in the plug body.

In this exemplification of the invention, when the screws 24 are tightened in effecting the connection between the conductor strands and the contact prongs, the soft rubber-like material 25 of the plug which is located between the members 22 and 28 is compressed and forced into gripping relation with respect to the end of the cord 26 whereby the plug cap is firmly anchored to the end of the cord.

30 In the various forms of plug caps just described, the effecting of the connection of the conductor strands of the cord serves also to anchor the plug cap to the end of the cord whereby the danger of separation of the plug with respect 35 to the cord, the breaking of the electrical connection between the conductor strands of the cord and the contact prongs, and the short circuiting between the conductor strands of the cord is greatly lessened if not wholly obviated and 40 a highly useful form of plug is provided which is of relatively simple and inexpensive construction and which may be readily clamped to the end of the cord by the means which are provided for effecting electrical connection between the 45 cord and the contact members of the plug.

Furthermore it is to be understood that the particular forms of apparatus shown and described, and the particular procedure set forth are presented for purposes of explanation and 50 that various modifications of said apparatus and procedure can be made without departure from this invention as described in the appended claims.

Having thus described my invention what I 55 claim is:

1. An attachment plug cap for use in connection with a flexible electric cord having conductor strands comprising a body formed from a soft rubber-like material having a central passage 60 way for the reception of the cord, a relatively rigid member embedded in said body and a second relatively rigid member spaced therefrom, contact blades carried by said last named member, and means engaging said embedded member for 65 connecting the conductor strands to said blades

and for drawing said rigid members together whereby the relatively soft material of the plug cap therebetween is compressed about the end portion of the cord for securely anchoring the plug cap thereto.

5

2. An attachment plug cap for use in connection with a flexible electric cord having conductor strands comprising, a pair of relatively rigid disk-like members with aligned apertures for receiving the cord, contact elements carried by one of said members, a resilient body surrounding said disk-like members providing a block of resilient material around the cord at the place where it traverses the members, and means for drawing said members toward each other for compressing the block of resilient material about the cord.

3. An attachment plug cap for use in connection with a flexible electric cord having conductor strands comprising, a pair of relatively rigid disk-like members with aligned apertures for receiving the cord, contact elements carried by one of said members, a block of resilient material surrounding the cord at the place where it traverses the members, and means for drawing said members toward each other for compressing the resilient body about the cord and also for effecting electrical connection between the strands of the cord and said contact elements.

4. An attachment plug cap for use in connection with a flexible electric cord having conductor strands comprising, a pair of relatively rigid disk-like members with aligned apertures for receiving the cord, contact elements carried by one of said members, a block of resilient material surrounding the cord at the place where it traverses the members, means for drawing said members toward each other for compressing the resilient body about the cord, and a body of resilient material integrally formed with said block surrounding said members.

5. An attachment plug for use in connection with a flexible cord having conductor strands comprising, a body formed from a resilient material having a central passageway for receiving the cord, relatively rigid members in said body spaced from each other by a portion of said body, contact terminal elements carried by one of said members, and means engaging said members for drawing them toward each other and for compressing the interposed portion of said body about said cord.

6. An attachment plug for use in connection with a flexible cord having conductor strands comprising, a body formed from a resilient material having a central passageway for receiving the cord, relatively rigid members in said body spaced from each other by a portion of said body, contact terminal elements carried by one of said members, and means engaging said members for drawing them toward each other for compressing the interposed portion of said body about said cord and for effecting connection of the conductor strands to said terminal members.

EDMUND J. TE PAS. 65
